(57) **CLAIM**

The ornamental design for a bottle, as shown and described.

DESCRIPTION

FIG. 1 is a top perspective view of a bottle, showing my new design;

FIG. 2 is a bottom perspective view thereof;

FIG. 3 is a front elevation view thereof, the rear elevation view being a mirror image thereof;

FIG. 4 is a right elevation view thereof, the left elevation view being a mirror image thereof;

FIG. 5 is a top plan view thereof; and,

FIG. 6 is a bottom plan view thereof.

The evenly spaced broken lines shown in the drawings depict portions of the bottle that form no part of the claimed design.

The dash-dot-dash broken lines shown in the drawings denote the boundaries of the claim and form no part thereof.

1 Claim, 4 Drawing Sheets
